F. KELLER

CUFF LINK

Filed Oct. 23. 1922

INVENTOR
F. Keller
BY Munro & Co.
ATTORNEYS

UNITED STATES PATENT OFFICE.

FRANK KELLER, OF CHICAGO, ILLINOIS.

CUFF LINK.

Application filed October 23, 1922. Serial No. 596,262.

To all whom it may concern:

Be it known that I, FRANK KELLER, a citizen of the United States, and a resident of Chicago, in the county of Cook and State of Illinois, have invented a new and useful Improvement in Cuff Links, of which the following is a full, clear, and exact description.

My invention relates to improvements in cuff links, and more particularly to that type of cuff link comprised of a pair of separable members, one of which is secured in each of the adjacent fastening portions of the cuff, and it consists in the combinations, constructions, and arrangements herein described and claimed.

An object of my invention is to provide a cuff link of the character described in which the separable members are normally locked positively against disengagement from one another when applied to the cuff link.

A further object of my invention is to provide a cuff link of the character described in which the mechanism for locking the links one to another is entirely encased within the tubular portion of the link.

A further object of my invention is to provide a device of the character described which is compact in form, is durable and practical for the purpose intended.

Other objects and advantages will appear in the following specification, and the novel features of the invention will be particularly pointed out in the appended claims.

My invention is illustrated in the accompanying drawings, forming part of this application, in which—

Figure 1 is a sectional view of an embodiment of my invention,

Figure 2 is a sectional view along the line 2—2 of Figure 1, and

Figure 3 is a sectional view along the line 3—3 of Figure 1.

In carrying out my invention, I make use of a pair of separable members 1 and 2, each formed of a tubular body member 3 and 4, respectively. The body members 3 and 4 are provided at each end with circular caps 5, 6, 7, and 8, respectively. Each of the cap members are arranged to extend beyond the outer wall of the body members 3 and 4 substantially as shown in Figure 1 and may be secured to the body members by any well known means, such as welding, soldering, or the like.

The link 1 has longitudinally disposed in

its body member 3 a resilient U-shaped tongue 9. The tongue is secured at its inner end 10 to the inner face of the cap 5. An opening 11 is provided through the cap 6 and the tongue extends therethrough and terminates in a substantially spherical portion 12. From inspection of Figure 1 it may readily be seen that the diameter of the spherical portion 12 may be greatly reduced by forcefully pressing the opposite portions 13 and 14 of the spherical portion toward one another as in passing through an opening 15 provided through the cap 7. This opening 15 in the cap 7 is arranged to permit the entrance of the spherical portion 12 of the tongue 9 therethrough, provided there is nothing to prevent the movement of the portions 13 and 14 toward one another.

Means for preventing the movement of the portions 13 and 14 toward one another when the spherical portion 12 has been inserted through the opening 15 in the cap 7, i. e., within the tubular portion 4 of the link 2, is provided as follows. The link has centrally located therethrough an opening 16, through which a bolt member 17 is slidably projected. The outer end of the bolt 17 is provided with a disc 18 that is slightly larger in diameter than the cap 8 (see Figure 1). This disc 18 normally lies in close proximity to the cap 8 and thus manually moved away from the cap in the manner heretofore described. The bolt 17 has on its outer end a cone-shaped portion 19. This cone-shaped portion 19 is arranged to be received in a cavity formed in the adjacent walls 20 of the portions 13 and 14 of the spherical head 12. In Figure 1 I have shown the cone-shaped portion in engagement with the aforesaid cavity. The bolt portion 17 has radially extending therefrom a circular flange 21 by means of which lateral movement of the bolt 17 in the tubular member 4 is obviated.

Means for locking the bolt 17 in the position shown in Figure 1 is provided in a pivotally mounted latch member 22 mounted upon the bolt 17 at 23. The latch member 22 is yieldably forced away from the bolt member 17 by means of a band spring 24. The outer end of the latch member 22 is adapted to extend through an opening 25 centrally located in the disc 18 and is provided with an ornamental finger grip 26 by means of which the latch 22 may be manu-

ally moved against the action of the spring 24 to fall entirely within the slot 27 provided in the bolt 17 for receiving the latch member. When the latch member is in this position, 5 the disc 18 may be manually drawn away from the link 2 and the entire bolt will move therewith, thereby breaking the contact of the cone-shaped portion 19 with the spherical portion 12 of the tongue 9.

10 From the foregoing description of the various parts of the device, the operation thereof may be readily understood. In using my improved cuff link, I insert the link 1 in one portion of the cuff, i. e., that 15 portion which is most visible as the cuff lies upon the arm of the wearer, and the link 2 is inserted in the opposite fastening portion of the cuff, so that the disc 18 normally faces toward the body of the wearer.

20 The latch member 22 is then manually moved by means of the finger grip 26 and the disc 18 drawn away from the link, causing the bolt 17 to be drawn so that 25 its conical portion 19 is out of the region of that portion 15 of the cap 7. The link 2 is then moved so that its cap is in contact with the cap 7 of the link 2 and the spherical portions 12 and 13 of the resilient tongue 9 has been forced through the opening in portion 15. The disc 18 is then pressed toward the link 2 until the conical portion 19 of the bolt 17 has engaged with the opposite portions 13 and 14 of the spherical member. 30 These portions will therefore be positively locked against movement toward one another by the interposed conical portion 19, and therefore may not move through the opening in the portion 15, even though extreme force be applied, tending to separate the 35 links. When the disc 18 is moved into contact with the cap 8, the latch 22, by virtue of the spring 24, will move upwardly and its toothed portion 29 will engage with the inner wall of the cap 8, thereby preventing the 40 accidental withdrawal of the disc 18 from the cap 8. The links are therefore positively locked in engagement with one another.

In order to remove the links one from another, it is merely necessary to manually 50 move the member 22 so that the toothed portion 29 is out of engagement with the cap 8 in the manner heretofore described, and withdraw the disc 18 from immediate 55 proximity with the cap 8. The portions 13 and 14 may thereupon move toward one

another as the links 1 and 2 are forcefully moved apart.

I claim:

1. A device of the character described comprising a pair of separable link members adapted to be held in the opposite fastening portions of a garment cuff, a tongue disposed in one of said links and extending exteriorly thereof, said tongue having a contractible enlarged head portion, the opposite link being provided with a restricted opening through which said head portion may be projected when in its contracted condition, and a bolt disposed within the last named link arranged to be moved into engagement with said contractible head portion for preventing the contraction of said head portion and thereby locking said links one to another. 60 65

2. A device of the character described comprising a pair of separable link members adapted to be held in the opposite fastening portions of a garment cuff, a tongue disposed in one of said links and extending exteriorly thereof, said tongue having a contractible enlarged head portion, the opposite link being provided with a restricted opening through which said head portion may be projected when in its contracted condition, a bolt disposed within the last 70 75 named link arranged to be moved into engagement with said contractible head portion for preventing the contraction of said head portion and thereby locking said links one to another, and means for yieldably locking said bolt in engagement with said contractible head portion. 80 85 90

3. A device of the character described comprising a pair of separable link members adapted to be held in the opposite fastening portions of the garment cuff, a tongue disposed on one of said links and extending exteriorly thereof, said tongue being split longitudinally for a portion of its length to form a contractible head portion, the opposite link being provided with a restricted opening through which said contractible head portion may be projected when in its contracted position, and a bolt disposed on said last named link and arranged to partially enter the split portion of said tongue, thereby preventing the contraction of the head portion of said tongue, and to cause said links to become locked to one another. 95 100 105
